UNITED STATES PATENT OFFICE.

FLORENCE VIOLETTE, OF MINNEAPOLIS, MINNESOTA.

DESIGN FOR A TABLE.

SPECIFICATION forming part of Design No. 34,090, dated February 12, 1901.

Application filed January 16, 1901. Serial No. 43,540. Term of patent 14 years.

To all whom it may concern:

Be it known that I, FLORENCE VIOLETTE, a citizen of the United States, residing at Minneapolis, in the county of Hennepin and State of Minnesota, have invented and produced 5 a new and useful Design for Tables, of which the following is a specification.

My invention is a design for tables; and it consists in the shape and configuration hereinafter described, and illustrated in the accompanying drawing.

The drawing is a side elevation of a table embodying the design.

The reference-numeral 1 designates a stand 15 and supported upon a plurality of curved legs 2, the sides of which are suitably ornamented and the outer edges of which are ornamented by scalloped projections 3, headed pins 4 projecting between the scallops. At 20 the upper end of the standard 1 is arranged a receptacle 5, comprising a plurality of curved fingers, and below the receptacle 5 are arranged three parallel platforms, (designated by the numerals 6, 7, and 8.) These platforms 25 are of graduated sizes, as shown, and each is provided with a plurality of upwardly-projecting pins 9. Below the lowermost platform 8 is located a table 10, supported upon

a platform 11, and below said platform 11 a semicircular receptacle 12 is arranged upon 30 the standard 1, said receptacle resting upon a support 13 and comprising radially-arranged wires or rods 14, the upper ends of which are connected by a ring 15, from which project lateral pins 16. From the under surface of 35 the ring 15 depend a plurality of tassels 17. The lower ends of the supporting-legs 2 are secured to vertically-disposed feet 18.

The leading feature of my design is the location of the several platforms above the table 10 and the semicircular receptacle 12 arranged concentric to the table 10 and below the latter.

Minor features of the design are the ornamented curved legs and the receptacle 5 at 45 the upper end of the standard.

I claim—

The design for a table as herein shown and described.

In testimony whereof I affix my signature 50 in presence of two witnesses.

FLORENCE VIOLETTE.
